United States Patent Office.

ROBERT H. LECKY, OF ALLEGHENY CITY, PENNSYLVANIA.

Letters Patent No. 79,361, dated June 30, 1868; antedated June 13, 1868.

IMPROVEMENT IN PIPE-WRENCH.

The Schedule referred to in these Letters Patent and making part of the same.

TO ALL WHOM IT MAY CONCERN:

Be it known that I, ROBERT H. LECKY, of the city and county of Allegheny, in the State of Pennsylvania, have invented a new and useful Improvement in Pipe-Wrench and Cutter combined in one instrument; and I do hereby declare that the following is a full and exact description thereof, reference being had to the accompanying drawings, and to the letters and figures of reference marked thereon.

The nature of my invention consists in combining in one instrument a pipe-wrench and cutter, constructed, arranged, and operating in the manner hereinafter described.

To enable others skilled in the art to make and use my invention, I will proceed to describe its construction and operation.

In the accompanying drawings, which form part of my specification—

Figure 1 is a side view of my improvement when arranged as a pipe-cutter.

Figure 2 is a side view of the tongue or clamp, which is used for converting or changing the instrument into a pipe-wrench.

In the drawings, A represents the jaw of the wrench and cutter, which is made in the form represented in fig. 1, and is provided with an opening, recess, or cavity, made in the form indicated by the dotted lines *x* and *m* for the reception of the cutter C and tongue or clamp C'. The opening or cavity in the jaw A should fit close to the sides of the cutter and tongue or clamp, and that part of the cavity in which that portion of the cutter or tongue marked D is pivoted, should fit very exact, as indicated by the dotted lines, marked *m*, in fig. 1, so as to form a hinged knuckle or socket-joint, so that all strain on or against the cutter C or tongue C' will come on the circular part marked D, thereby relieving the pin *n* from the strain or force brought to bear on the cutter C or tongue C'. The only office required of the pivot-pin *n* is to hold the cutter or tongue to its place in the jaw A. The pivot-pin *n* is fitted in the opening marked *a*.

The cutter C is provided with a cutting-edge, *f*, for cutting off the pipe, and a series of cutters, marked *e*, which are used for cutting off the burr or swell on the pipe, caused by the cutting-edge *f*. The gripping edge of the tongue or clamp C' should be provided with fine teeth or corrugations, so that it will readily grasp the pipe placed in the jaw A.

From the foregoing description, and by reference to the accompanying drawings, the skillful mechanic will readily understand the construction of my improvement in pipe-wrench and cutter as combined in one instrument.

I will therefore proceed to describe the operation of my improvement.

In cutting off gas or other pipes, the cutter C is placed in the jaw A, and the pipe is placed between the cutter and jaw, the cutter is pressed against the pipe, and then, by drawing the lever B, the cutting-edge *f* will be forced into and cut the pipe in proportion to the draught on the lever B, and the burr or swell formed on the pipe by the action of the cutting-edge *f* will be cut off by the cutters *e*, thereby keeping the end of the pipe to the desired diameter. I convert the instrument into a pipe-wrench by removing the cutter C, and putting in its place the tongue or clamp C'. The pipe is placed between the tongue or clamp, and by drawing the lever B, the tongue or clamp will grasp the pipe in proportion to the draught on the lever.

The advantages of my improvement consist in being enabled, by the use of one instrument, to cut, trim off, and wrench pipes of different diameters.

I wish it clearly understood that I do not claim broadly an eccentric-cutter or clamp in pipe-cutters or wrenches.

Having thus described the nature, construction, and operation of my improvement, what I claim as of my invention, is—

A pipe-wrench and cutter combined in one instrument, constructed, arranged, and operating substantially as herein described, and for the purpose set forth.

R. H. LECKY.
